Atty.

UNITED STATES PATENT OFFICE.

FRANK L. GORMLEY, OF BROOKLINE, MASSACHUSETTS, ASSIGNOR TO A. O. NORTON, INC.,
OF BOSTON, MASSACHUSETTS, A CORPORATION.

GOVERNOR.

1,324,346.

Specification of Letters Patent.

Patented Dec. 9, 1919.

Application filed July 23, 1919. Serial No. 312,820.

To all whom it may concern:

Be it known that I, FRANK L. GORMLEY, a citizen of the United States of America, and a resident of Brookline, county of Norfolk, and State of Massachusetts, have invented certain new and useful Improvements in Governors, of which the following is a specification.

This invention relates to governors and particularly devices of this character which are adapted to operate by centrifugal action to retard the speed of a revoluble shaft when it exceeds a predetermined limit.

The invention consists primarily of a member revoluble with a rotating shaft, having pivoted thereto weighted arms, having cam projections thereon adapted to bear against the inner faces of diametrically disposed friction members which are adapted to be moved radially into contact with the wall of a housing for said revoluble member whenever said arms are moved outwardly about their pivots by centrifugal action due to the excessive speed of said rotating shaft.

The invention further consists of certain novel features of construction and arrangement of parts which will be fully understood by reference to the description of the drawings and to the claims to be hereinafter given.

For the purpose of illustrating the invention, one preferred form thereof is illustrated in the drawings, this form having been found to give satisfactory and reliable results, although it is to be understood that the various instrumentalities of which the invention consists can be variously arranged and organized, and that the invention is not limited to the precise arrangement and organization of the instrumentalities as herein shown and described except as required by the scope of the appended claims.

Of the drawings:

Figure 1 represents a vertical section of a housing showing in elevation a governor embodying the features of the present invention.

Fig. 2 represents a vertical section of the governor, and its housing.

Fig. 3 represents an end view of the governor, and

Fig. 4 represents an elevation of the governor disk with one of the slidable friction members.

Similar characters indicate like parts throughout the several figures of the drawings.

In the drawings, 10 is a fixed support having a bearing 11 for a revoluble shaft 12 and provided also with a cylindrical chamber 13 concentric to the axis of said shaft 12.

The shaft 12 has a disk 14 secured thereto, and revoluble therewith, said disk closing the open end of said chamber 13.

The disk 14 is provided with two diametrically disposed grooves 15 and a central hub 16 from which said grooves 15 radiate. At the outer end of each groove 15 is a projecting stop member 17.

In each groove 15 is positioned a rib 18 of a slidable friction member 19 the outer end of which is provided with a broad pad 20 the outer face of which is curved to fit the cylindrical wall of the chamber 13.

The inner faces 21 of the pads 20 are perpendicular to the grooves 15 and form bearing surfaces for the pivoted actuating levers 22 to act upon.

The levers 22 are mounted upon pivots 23 screwed into the disk 14 and having heads 25 to prevent the displacement of said levers 22. The inner face of the rib 18 of each slidable member 19 is provided with a recess 26 extending from the outer end of the pad 20 to a point substantially midway the length of said slidable member.

In each recess 26 is disposed a helical spring 27 one end of which bears against the inner end of the recess 26 and the opposite end of which bears against the projecting stop member 17. The springs 27 normally retain the inner ends of the slidable members 19 in contact with the hub 16.

The levers 22 are provided with weights 28 on their outer ends and intermediate the ends of said levers are cam shaped projections 29, each bearing against the inner flat face 21 of a pad 20.

Under normal conditions there will be slight clearance between the friction pad 20 and the cylindrical wall of the chamber 13.

When the shaft 12 begins to rotate at an excessive speed, the centrifugal action will throw the weights 28 outwardly and the outward movement of the projections 29 will cause the pads 20 to be forced into frictional contact with the cylindrical wall of the chamber 13 and this friction will tend to retard the rotation of said shaft.

It is obvious that the faster the shaft 12 rotates, the greater will be the frictional contact between the pads 20 and the chamber wall.

5 In order to increase the force imparted to the slideable member 19 when it is being moved into engagement with the chamber wall, the projection 29 is located substantially midway between the outer end of the 10 lever 22 and its pivot pin or stud 23.

By providing the slideable member 19 with a rib 18 positioned in the groove 15, the movement of said slideable member is always in a straight path radial to the axis of the 15 shaft 12.

By moving the friction members 19 in a radial path, the bearing surface of the pads 20 coacting with the chamber wall will always wear evenly and consequently the entire surfaces thereof will impinge upon said wall under all conditions and a better frictional contact is thereby assured.

20 By constructing the governor in the manner shown and described, all of the operating parts may be confined in very small chambers and great leverage may be attained.

25 The governor is particularly adapted for use in connection with self-run-down screw jacks.

It is believed that the operation and many advantages of the invention will be readily understood without further description.

Having thus described my invention, I 30 claim:

1. In a device of the class described, a cylindrical housing closed at one end; a revoluble shaft; a circular disk thereon positioned within the open end of said housing 40 and having oppositely disposed radial grooves in one face; friction members slideably mounted in the grooves of said disk and adapted to coact with the cylindrical wall of said housing; and pivoted weighted members for actuating said slideable members.

2. In a device of the class described, a cylindrical housing closed at one end; a revoluble shaft; a circular disk thereon positioned within the open end of said housing 50 and having oppositely disposed radial grooves in one face; friction members slideably mounted in the grooves of said disk and adapted to coact with the cylindrical wall of said housing, said friction members

each having a longitudinal recess on its inner face; springs in said recesses for normally retaining said members free from contact with the chamber wall; and pivoted weighted members for actuating said slideable members.

3. In a device of the class described, a cylindrical housing; a revoluble shaft; a disk thereon having oppositely disposed radial grooves in one face and a projecting stop at the outer end of each groove; friction members slideably mounted in the grooves of said disk and adapted to coact with the cylindrical wall of said housing, said friction members each having a recess on the inner face; springs in said recesses with their outer ends bearing against said stops; and pivoted weighted members for actuating said slideable members.

4. In a device of the class described, a cylindrical housing; a revoluble shaft; a disk thereon having a central hub and radial grooves on one face and a projecting stop at the end of each groove; friction members slideably mounted in the grooves of said disk and adapted to coact with the cylindrical wall of said housing; springs for normally retaining said slideable members in contact with said hub; and pivoted weighted members for moving said slideable members outwardly against the tension of said springs.

5. In a device of the class described, a cylindrical housing; a revoluble shaft; a disk thereon having a central hub and radial grooves on one face; and a projecting stop at the end of each groove; friction members having ribs positioned in said grooves and each provided with a recess on its inner face into which said stop member extends; springs in said recesses and bearing against said stop members to normally retain said friction members against said hubs; and pivoted weighted members having cam portions intermediate their ends bearing against shoulders on said friction members and adapted to move said friction members outwardly.

Signed by me at 4 Post Office Sq., Boston, Mass., this 21st day of July, 1919.

FRANK L. GORMLEY.
